Primary Examiner — Eric Goodman*Assistant Examiner* — Amy Wierenga(74) *Attorney, Agent, or Firm* — Fish & Richardson P.C.(57) **CLAIM**

The ornamental design for a coupling, as shown and described.

DESCRIPTION

FIG. 1 is perspective view of the coupling.

FIG. 2 is a side view of the coupling.

FIG. 3 is an end view of the coupling; and,

FIG. 4 is a top view of the coupling.

The broken lines depict portions of the coupling that form no part of the claim.
